FLUID PRESSURE PRODUCING DEVICE

Clarence H. Bock, Detroit, Mich., assignor to
 Hydraulic Brake Company, Detroit, Mich., a
 corporation of California

Application December 14, 1935, Serial No. 54,507

5 Claims. (Cl. 60—54.6)

This invention relates to fluid pressure brake systems and more particularly to fluid pressure producing devices for such systems.

Heretofore in the construction of fluid pressure producing devices having a fluid reservoir, a cylinder supplied therefrom, and a piston reciprocable in the cylinder, the cylinder has generally been supplied with two ports providing communications between the cylinder and the reservoir. These ports are generally known as the supply port and the compensating port. The latter is located slightly in advance of a flexible cup seated on the head of the piston when the piston is in retracted position. Hence, when the piston is moved on its compression stroke the pressure created in the cylinder forces the wall of the cup into the port and this results in serious injury to the cup. The present invention aims to overcome this objection.

An object of the invention is to provide a combined supply and compensating port for a fluid pressure producing device.

Another object of the invention is to provide a fluid pressure producing device including a reservoir, a cylinder communicating therewith, a piston reciprocable in the cylinder, and means for control of the communication between the reservoir and the cylinder so that the communication functions as a combined supply and compensating port.

Other objects of the invention will appear from the following description taken in connection with the drawing which form a part of this specification, and in which,—

Fig. 1 is a schematic view of a fluid pressure brake system embodying the invention;

Fig. 2 is a vertical sectional view of the fluid pressure producing device of the system showing the positions assumed by the parts while the system is under pressure; and

Figure 3 is an enlarged view of the mechanism interposed between the compression cylinder and the reservoir showing the parts in the positions assumed when the system is not under pressure.

Referring to the drawing for more specific details of the invention, 10 represents a reservoir having a filling opening 12 which may be closed by a plug 14 having openings 16 for venting the reservoir to the atmosphere. The reservoir has a dependent sleeve or chamber 18 communicating therewith and vented to the atmosphere as indicated at 20, the purpose of which will hereinafter appear.

A cylinder 22 formed normal to the base of the chamber 18 has a port 24 adjacent its head pro-

viding a communication between the cylinder and the chamber, and this port is controlled by a valve mechanism housed in the chamber. The cylinder also has a discharge port 26 controlled by a two-way valve 28.

As shown, the valve mechanism for controlling the port 24 includes a double diametral piston 30 reciprocable in the chamber 18 and a hollow plug 32 threaded in the open end of the chamber having an aperture 34 providing a communication between the chamber and the reservoir 10. The plug 32 receives the small end of the piston, and a set screw 36 in the wall of the plug limits the movement of the piston.

The piston has oppositely disposed heads 38 and 40 and a projection 42 on the head 40 having a frusto-conical end 44 adapted to seat in the aperture 34 in the plug 32. The body of the piston and the projection 42 are axially bored to provide a chamber 46 and a passage 48 communicating with the chamber 46, and the passage 48 communicates with a diametral passage 50 in the projection 42.

A leak-proof cup 52 sleeved on the projection 42 and seated on the head 40 provides against seepage of fluid past the piston, and a spring 54 interposed between the plug 32 and the shoulder on the piston normally urges the piston toward the bottom of the chamber 18 to move the frusto-conical end 44 on the projection 42 from its seat in the aperture 34 to establish communication between the reservoir 10 and the cylinder 22.

The passage 48 is controlled by a flap valve 56 having a restricted opening 58. A spring 60 interposed between the valve 56 and a ring washer 62, pressed into the open end of the chamber 46, normally urges the valve 56 to its seat, and a leakproof cup 64 held on the head 38 of the piston by a spring 66 provides against seepage of fluid past the piston. The valve 56 with its restricted opening 58 cooperates in the creation of sufficient pressure beneath the piston valve 30 to close this valve against the resistance of the spring 54 when pressure is created in the cylinder 22.

A fluid pressure delivery pipe or conduit 68 suitably connected to the discharge port 26 has branches connected respectively to fluid pressure actuated motors 70 arranged for the actuation of brakes associated with the wheels of a motor vehicle. The brakes may be of conventional type arranged in pairs, one pair for the front wheels of the vehicle and the other pair for the rear wheels of the vehicle.

As shown, each of the brakes includes a fixed support or backing plate 72, a rotatable drum 74 associated therewith, a pair of corresponding interchangeable friction elements or shoes 76 pivoted on the backing plate, and a fluid pressure actuated motor corresponding to the motors 70 arranged on the backing plate and operative to move the shoes into engagement with the drum against the resistance of the retractile springs 78 connected between the shoes.

A piston 80, reciprocable in the cylinder 22, is retained in the cylinder by a washer 82 seated on an annular shoulder in the open end of the cylinder and secured in place by a retaining ring 84 seated in a groove in the wall of the cylinder. A leakproof cup 86 seated on the head of the piston is held against displacement by a spring 88 interposed between the cup and the two-way valve 28. This spring also serves to return the piston to its retracted position. A recess 90 in the back of the piston receives one end of a thrust pin 92 on the other end of which is a coupling 94 connected by a flexible boot 96 to the open end of the cylinder for the exclusion of dust and other foreign substances. The coupling 94 is connected by a rod 98 to a foot pedal lever 100 pivoted on a suitable support 102, and the lever is connected by a retractile spring 104 to a fixed support 106.

30 In operation, upon depressing the foot pedal lever 100 force is transmitted from this lever to the piston 80, resulting in moving the piston on its compression stroke. During the initial movement of the piston the fluid under pressure in the cylinder 22 and the chamber 18 causes actuation of the piston 30 resulting in closing the port 34 and thereby cutting off communication between the cylinder 22 and the reservoir. Upon further movement of the piston on its compression stroke fluid is expelled from the cylinder 22 past the two-way valve 28, which inhibits retrograde movement of the fluid, and through the fluid pressure delivery pipe 68 and its branches into the fluid pressure actuated motors 70, causing actuation of the motors with the resultant spreading of the shoes 76 into engagement with the drums against the resistance of the retractile springs 78.

Upon release of the foot pedal lever 100, this lever is returned to its normal position under the influence of the retractile spring 104. As the foot pedal lever moves to its retracted position, the thrust pin 92 connected thereto is retracted. This results in release of the piston 80, whereupon the spring 88 becomes effective to return the piston to its retracted position. Upon the initial movement of the piston on its retraction stroke, pressure on the piston 30 is released and the piston moves under the influence of the spring 54 to its retracted position, resulting in opening the port 34 and thus establishing communication between the cylinder 22 and the reservoir 10. Upon further movement of the piston on its retraction stroke, fluid is drawn from the reservoir through the passage 48 in the piston 30, past the valve 56 which moves downwardly to permit free flow of fluid from the reservoir to the cylinder 22, and through port 24 into the cylinder 22.

70 During this operation fluid is returning to the cylinder 22 from the motors 70 under the influence of the retractile springs 78, and when the cylinder is filled any fluid in excess of the quantity required to completely fill the cylinder is returned through the port 58 in the valve 56, the

passage 48 in the piston, and the port 34 to the reservoir.

It will be observed that should any expansion or contraction of the fluid occur in the system due to changes in temperature, such expansion or contraction is readily compensated for by the flow of fluid through the port 58 in the valve 56.

Although this invention has been described in connection with certain specific embodiments, the principles involved are susceptible of numerous other applications that will readily occur to persons skilled in the art. The invention is, therefore, to be limited only as indicated by the scope of the appended claims.

Having thus described the various features of the invention, what I claim as new and desire to secure by Letters Patent is,—

1. A fluid pressure producing device comprising a reservoir, a chamber communicating therewith, a cylinder communicating with the chamber, a piston reciprocable in the cylinder, a piston valve reciprocable in the chamber and having a passage therethrough, a valve for control of the passage, said last mentioned valve having a restricted opening therethrough registering with said passage, said piston valve being normally positioned to provide communication between the cylinder and reservoir and being responsive to the increase of pressure in the cylinder upon advance of the piston to close such communication, and means for actuating the piston.

2. A fluid pressure producing device comprising a reservoir, a chamber communicating therewith, a cylinder communicating with the chamber, a piston reciprocable in the cylinder for control of the communication between the reservoir and the chamber, said piston valve having a passage therethrough, said piston valve being normally positioned to provide communication between the reservoir and chamber but being responsive to the increase of pressure in the cylinder upon advance of the piston to close such communication, a spring pressed valve controlling the passage in the piston valve, said spring pressed valve having a restricted opening therethrough registering with said passage, and means for actuating the piston.

3. A fluid pressure producing device comprising a reservoir, a chamber communicating therewith, a cylinder having an inlet port providing communication between the chamber and the reservoir and a discharge port, a piston reciprocable in the cylinder, a piston valve in the chamber for control of communication between the reservoir and chamber, said piston valve having a passage therethrough, a spring pressed valve for control of the passage and having a compensating port, said piston valve being normally positioned to open said inlet port but being responsive to the increase of pressure in the cylinder upon advance of the piston to close the inlet port, and means for actuating the piston.

4. A fluid pressure producing device comprising a reservoir, a chamber communicating therewith, a cylinder having an inlet port providing communication between the chamber and the reservoir and an exhaust port, a piston reciprocable in the cylinder, a piston valve in the chamber for control of the communication between the reservoir and the chamber and having a passage therethrough, a spring normally retaining the piston valve in inlet port opening position, a spring pressed flap valve for control of the passage in the piston valve, said flap valve

having a compensating port, said piston valve being responsive to the increase of pressure in the cylinder upon advance of the piston to close the inlet port, and means for actuating the piston.

5. A fluid pressure producing device comprising a reservoir, a chamber communicating therewith, a cylinder having an inlet port providing a communication between the chamber and the reservoir and the discharge port, a two-way valve for control of the discharge port, fluid pressure actuating motors operatively connected to the

discharge port, a piston reciprocable in the cylinder, a piston valve in the chamber for control of communication between the reservoir and the chamber and having a passage therethrough, a spring pressed flap valve for control of the passage and having a compensating port, said piston valve being normally in position to open said inlet port but being responsive to the increase of pressure in the cylinder upon advance of the piston to close the inlet port, and means for actuating the piston.
